TABLET CONTAINER AND DISPENSER

Joshua Raschkind, New York, N. Y.

Application March 8, 1939, Serial No. 260,461

10 Claims. (Cl. 206—42)

The invention relates to a container for medicinal tablets in which container such tablets may be conveniently carried in a substantially closed condition protecting the contained tablets from dust and the effects of atmospheric conditions such as moisture, thereby keeping them in substantially their original condition of purity and cleanliness, while at the same time being capable of being dispensed from the container individually and without exposing the remaining tablets in the container to contact with dust and moisture of the atmosphere.

An object of the invention is to provide such a container, and dispensing closure device therefore, which is substantially compact, so as to be suitable for carrying the same about the person, for instance in a pocket of wearing apparel or in a purse, and thus make the contained tablets available for use in an emergency, for instance outside of the home or office.

A further object of the invention is to provide such a container and dispenser which is extremely simple in construction and therefore in cost of manufacture, and is characterized by an extreme simplicity in manipulation to permit the removal therefrom of one or more tablets individually.

In the accompanying drawing, I have illustrated two specific embodiments of my invention without defining its limits, the embodiments shown in such drawing being selected for purposes of illustration and are to be regarded as such rather than as limiting the nature of the invention. In such drawing, Fig. 1 is a plan view of a tablet container and dispenser constructed in accordance with my invention; Fig. 2 is a vertical section along the line 2—2 of Fig. 1; Fig. 3 is a plan view of the body of the container with the cover portion thereof, embodying the dispensing closure, removed therefrom; Fig. 4 is a vertical section through the cover member in a direction substantially at right angles to that of the section of Fig. 2, with such cover member positioned upon the container body;

Fig. 5 is a side view of the container; Fig. 6 is a bottom plan view of the cover member and closure structure embodied therein; and Fig. 7 is a plan view similar to Fig. 3 of a modified form of the body member of my novel tablet container. Referring more particularly to the drawing, in which similar reference characters identify similar parts in the several views, 10 is the body of the container which may suitably be molded or otherwise fabricated from any of the common position materials now on the market, for in-

stance, a phenolic condensation product. Such container body is constituted of the base portion 11, the upwardly extending peripheral rim 12 and an integrally formed inner rim or compartment 13. Connecting the outer or peripheral rim 12 and the inner rim 13 and formed integrally therewith are a plurality of radial ribs 14, as clearly shown in Fig. 3, which ribs and annular rims thus form a plurality of individual compartments 15 of sufficient size and configuration to accommodate a single medicinal tablet 16.

The upper surface of the container body 10, i. e. the free edge of the rim 12 is preferably formed rounded as at 17, with a circumferential track 18 between the rounded upper edge of the rim and the remainder of the container body, so that such rounded upper free edge constitutes a bead running substantially throughout the lip of the container body. Disposed substantially throughout the circumference of the track 18 at approximately the mid-point of each of the compartments 15 are an equal number of slight depressions 19 for a purpose hereinafter described more in detail.

The cover portion of my novel tablet container and dispenser, generally designated as 20, is constituted of a disc-like member 21 which preferably may be formed of a slightly resilient material, such as sheet metal, although it may be also formed of composition material, which disc has a depending flange or skirt portion 22, the lower extremity of which is provided with a slight curvature as at 23 so that when the cover 20 is superimposed upon the container body the curved extremity of the skirt portion 22 snaps into the track 18 of the body and moves in such track upon rotation of the cover upon the container body as hereinafter described. In order to facilitate the snapping of the cover portion upon the container body, and to permit its free rotation thereon, the skirt portion 22 is provided with a plurality of slits 24 extending vertically from the lower edge thereof to substantially near the disc portion of such cover.

The cover for my novel tablet container and dispenser is provided along substantially to one one side of its horizontal center line as defined by the section line 2—2 on Fig. 1 with a pair of ribs or beads 25 and 26, formed by pressing the material of the cover member outwardly. Between these ribs and extending from one edge of the cover to substantially its center is an opening 27. Supported for sliding movement between the ribs 25 and 26 and extending slightly thereunder, is a closure slide 28 which carries at its free end 55

an upwardly extending knob or button 29. The closure slide 28 is thus adapted to be moved by means of the knob 29 from a position in which it covers the opening 27, to a position in which it uncovers such opening by being slid backwardly along the ribs 25 and 26 to beneath the portion of the cover between the ribs 25 and 26, being stopped in its sliding movement either by the abutment of the knob 29 against the leading edge 10 of the portion of the cover disposed between the ribs 25 and 26, or by the abutment of the end of the slide against the inner surface of the cover. For controlling the sliding movement of the closure slide I may provide one or more projections 15 30 upon the upper surface thereof, which projection or projections are adapted to snap, in one or the other of the positions of the slide, into a correspondingly configured recess 31.

Supporting the slide 28 within its raceways 20 against the interior surface of the cover, is a cardboard liner 32, which may be secured within the cover in any suitable manner, for instance, by an adhesive, and which is provided with an opening 33 substantially of the configuration of one of the compartments 15 of the container body so as to permit the passage therethrough of the tablet contained in such compartment.

The assembling and manipulation of my novel tablet container and dispenser is as follows:

30 The container body, prior to the application thereto of the cover portion thereof, is filled with the tablets to be contained and to be dispensed therefrom, each tablet being positioned in an individual compartment 15. The filling of the container in this manner is an extremely simple operation capable of being accomplished by automatic machinery in which the container body may be positioned for rotation about its center and one tablet at a time permitted to be dropped 40 from a hopper or reservoir into the various compartments. The re-filling of the container by a consumer of the tablets is likewise extremely simple as the cover may be readily removed and each individual tablet may be merely positioned 45 over its individual compartment and dropped thereinto in which it will assume its proper position for being dispensed from the container when the cover is replaced thereover. Such cover, after the container body has thus been charged with 50 the tablets, may be snapped into position upon the container body when it may be rotated until the projection 19', provided upon the inner surface of the skirt 22 at the exact center of one 55 of the tablet compartments, snaps into one of the depressions 19. This position of the container will indicate the proper alignment of the opening 27 and therefore of the closure slide 28 with the center line of one of the compartments 15, thereby indicating that upon the movement of the closure slide to its retracted position beneath the portion of the cover between the ribs 25 and 26, a single tablet 16 may be removed from the container by turning the container upside down or 60 a mere flipping thereof sufficient to dislodge the tablet uncovered by the slide from the container body. If it is desired to dispense a second tablet, the cover portion may be rotated to the next succeeding depression 19 in either direction and the 65 tablet then uncovered removed from its compartment. The container may then be closed by sliding the closure 28 to its position in which it covers the opening 27 and the container is then ready for the next operation of dispensing a single 70 tablet, by rotation of the cover portion one more 75 tablet, by rotation of the cover portion one more

notch, or of the projection 19' to the next succeeding depression 19.

In Fig. 7, I have shown a slightly modified form of my invention. In such modified form, the container body is similarly constituted and substantially similarly shaped, but instead of having a plurality of ribs separating the individual tablets, the central rim 34 is provided with a number of radially extending truncated ribs 35 forming between them hollows 36, to accommodate one end 10 of each of the tablets, the ribs being equal in number to the number of tablets for which the container is designed, and the outer rim 37 has extending inwardly therefrom pairs of ribs 38, 38, forming between each pair of such ribs hollows 39 15 accommodating the outer portions of the tablets. With the exception of this modification in the form of the container body, the embodiment of my invention illustrated in Fig. 7 is substantially like that of the first and preferred embodiment, 20 the same type of cover and closure member and the features thereof hereinabove described being used.

While I have described specific embodiments of my invention, it will be obvious that various 25 changes therein, particularly in the arrangement and configuration of the several parts thereof, may be made without departing from my invention.

I claim:

1. A medicinal tablet container and dispenser comprising a body portion having an upwardly extending outer rim, an upwardly extending centrally disposed anchor, and integral radial ribs extending from said anchor to said outer rim, 35 forming uniformly spaced individual compartments for receiving and retaining the tablets in substantially vertically disposed upright position, a cover having a peripheral depending skirt and superimposed upon said body portion with the lower extremity of said skirt in frictional contact with the outer surface of said body portion, said cover having a radially extending opening extending from the center of the cover to its periphery and adapted to be brought into registry, 45 upon rotation of the cover, with a single tablet compartment, and a closure slide for said opening.

2. A medicinal tablet container and dispenser comprising a body portion having an upwardly extending outer rim, an upwardly extending centrally disposed anchor, integral radial ribs extending from said anchor to said outer rim, forming uniformly spaced individual compartments for receiving and retaining the tablets in substantially vertically disposed upright position, said 55 outer rim having a peripheral indented track near the upper edge thereof and a plurality of depressions therein, a cover having a peripheral depending skirt and superimposed upon said body portion with the lower extremity of said skirt disposed within said track, a projection extending inwardly from the skirt and adapted to enter one of the depressions in said body portion, said cover having a radially extending opening extending from the center of the cover to its periphery and 60 adapted to be brought into registry upon rotation of the cover, with a single tablet compartment, and a closure slide for said opening.

3. A medicinal tablet container and dispenser comprising a body portion having an upwardly 70 extending outer rim, and an upwardly extending inner rim, and integral radial ribs extending from said inner rim to said outer rim, forming individual compartments for the tablets, a cover having a peripheral depending skirt and super- 75

imposed upon said body portion with the lower extremity of said skirt in frictional, resilient contact with the outer surface of said body portion, said cover having a radially extending opening 5 adapted to be brought into registry, upon rotation of the cover, with a single tablet compartment, a pair of elongated beads forming tracks disposed to one side of a center line of said cover, a closure member slidable within said tracks, a knob extending upwardly from said closure member, and a liner for said cover having an aperture of a size and configuration permitting the passage therethrough of a single tablet.

4. A medicinal tablet container and dispenser 15 comprising a body portion having an upwardly extending outer rim, and an upwardly extending inner rim, and integral radial ribs extending from said inner rim to said outer rim, forming individual compartments for the tablets, said outer rim 20 having a peripheral indented track near the upper edge thereof, and a plurality of depressions therein, a cover having a peripheral depending skirt and superimposed upon said body portion with the lower extremity of said skirt disposed 25 within said track, said skirt having a plurality of slits extending upwardly from its lower extremity, and a projection extending inwardly from the skirt and adapted to enter one of the 30 depressions in said body portion, said cover having a radially extending opening adapted to be brought into registry upon rotation of the cover, with a single tablet compartment, a pair of elongated beads disposed to one side of a center line of said cover, a closure member slidable 35 within tracks formed by said beads to beneath the cover portion between said beads, a knob extending upwardly from said closure member and a liner for said cover having an aperture of a size and configuration permitting the egress of 40 a single tablet from one of said compartments.

5. A medicinal tablet container and dispenser comprising a body portion having an upwardly extending outer rim, an upwardly extending inner rim, and radial ribs extending from said 45 inner rim and from said inner rim and from said outer rim, said outer rim having a peripheral indented track near the upper edge thereof, and a plurality of depressions therein, a cover having a peripheral depending skirt superimposed upon 50 said body portion with the lower extremity of said skirt disposed within said track, said skirt having a plurality of slits extending upwardly from its lower extremity, and a projection extending inwardly from one point thereon and 55 adapted to enter one of the depressions in the outer rim of said body portion, said cover having a radially extending opening adapted to be brought into registry, upon rotation of the cover, with a single tablet, a pair of ribs disposed to 60 one side of the center line of said cover, a closure slide for said opening slidable beneath said ribs to extend under the cover portion between said ribs, a knob extending upwardly from said closure slide, and a liner for said cover having an aperture of a size and configuration permitting the 65 egress of a single tablet from one of said compartments.

6. A medicinal tablet container and dispenser comprising a body portion having an upwardly 70 extending outer rim, an upwardly extending centrally disposed anchor, and integral radial ribs extending from said anchor outwardly and from

said outer rim inwardly, forming uniformly spaced individual retaining hollows receiving and retaining for the tablets in substantially vertically disposed upright position, a cover having a peripheral depending skirt and superimposed upon said body portion with the lower extremity of said skirt in frictional contact with the outer surface of said body portion, said cover having a radially extending opening extending from the center of the cover to its periphery and adapted to be 10 brought into registry, upon rotation of the cover, with a single tablet compartment, and a closure slide for said opening.

7. A medicinal tablet container and dispenser 15 comprising a body portion having an integral outer rim and a centrally disposed anchor, means associated with said rim and anchor to form a plurality of individual compartments for tablets to receive and retain such tablets in substantially vertically disposed upright position, a cover for 20 said body portion adapted to be resiliently snapped on the outer rim thereof and having an elongated aperture in the upper surface thereof the size of the width of a tablet in such vertically disposed, upright position and adapted to 25 be brought into registry, upon rotation of the cover upon said body portion, with one of the tablets in said compartment.

8. A medicinal tablet container and dispenser 30 as claimed in claim 7, in which the cover member is provided with a closure slide and at each side of the closure slide with a pair of tracks for permitting sliding movement of said closure to positions covering and uncovering the aperture in the surface of said cover.

9. A medicinal tablet container and dispenser comprising a body portion having an upwardly extending outer rim, and an upwardly extending inner rim, and integral radial ribs extending from said inner rim to said outer rim, forming individual compartments for the tablets, a cover having a peripheral depending skirt and superimposed upon said body portion with the lower extremity of said skirt in frictional, resilient contact with the outer surface of said body portion, 45 said cover having a radially extending opening adapted to be brought into registry, upon rotation of the cover, with a single tablet compartment, a pair of elongated beads forming tracks disposed to one side of a center line of said cover, 50 a closure member slidable within said tracks, a knob extending upwardly from said closure member, and a liner for said cover having an aperture of a size and configuration permitting the passage therethrough of a single tablet, said 55 closure slide being provided with a projection extending upwardly from the surface thereof and said cover having a pair of recesses into either of which said projection is adapted to extend to maintain the closure slide in either of its 60 opening or closing position.

10. A medicinal tablet container and dispenser 65 as claimed in claim 7, in which the outer rim of the body portion is provided with an inwardly curved track having a plurality of depressions corresponding to the number of tablet compartments, and the cover member is provided with a projection sliding within said track upon rotation of the cover and adapted to enter one of said depressions in said track.
